UNITED STATES PATENT OFFICE.

HAROLD W. EDEN, OF CHICAGO, ILLINOIS.

RECIPROCATING POSITIONING MECHANISM.

1,149,814.

Specification of Letters Patent. Patented Aug. 10, 1915.

Application filed January 26, 1914. Serial No. 814,412.

To all whom it may concern:

Be it known that I, HAROLD W. EDEN, a citizen of the United States and a resident of the city of Chicago, in the county of Cook and State of Illinois, have invented certain new and useful Improvements in Reciprocating Positioning Mechanism; and I do hereby declare that the following is a full, clear, and exact description of the same, reference being had to the accompanying drawings, and to the numerals of reference marked thereon, which form a part of this specification.

Heretofore in power driven washing machines in which the clothes are contained within a reciprocating drum, it has been more or less difficult to properly locate the opening in said drum for the purpose of inserting or removing clothes therefrom when the drive has been thrown off, and in most instances it has been necessary to alternately drive and stop the machine until the clothes drum stops at a certain position convenient for affording access thereto.

This invention relates to a reversing gear adapted to reciprocate a clothes drum and so connected thereto as to properly position the same when the same is brought to rest, with the opening conveniently accessible from the top of the machine, whereby the contents of the drum may be easily removed therefrom without loss of time usually required in an endeavor to locate and position the opening.

It is an object of this invention to construct a rotatable clothes drum associated with suitable reciprocating gearing adapted to alternately drive said drum first in one direction and then in another and with means for stopping said drum in a position with the opening therein properly disposed for access by an operator.

It is also an object of this invention to provide a clothes drum having doors therein, said drum associated with suitable gears for reciprocating the same, the reciprocating mechanism so timed as to reverse the drive when the doors in the drum are at the top thereof whereby a stopping of the same effected at such a point affords convenient access thereto by an operator.

It is also an object of this invention to provide a reciprocating gear for a clothes drum, wherein the reversal of drive takes place when the doors in said drum are in

an upper position and with manually actuatable means for locking the reversing gear in neutral position to disconnect the drive from the drum with the doors therein properly positioned for convenient access thereto.

It is also an object of this invention to provide a reversing gear connected with a clothes drum having doors therein, said reversing gear so timed as to effect a reversal of said drum when the doors are in an upper position and with means for disconnecting the reversing gear or retaining the same in neutral position at the instant of reversal of said drum to thereby stop the same with said doors in said upper position.

It is furthermore an object of this invention to construct a device wherein a clothes drum having doors therein is adapted to be driven by a reversible or reciprocating mechanism, which acts automatically to reverse the direction of drive of said drum periodically, and with a manually actuated pin adapted to stop an element of the reversing mechanism during a reversing movement thereof to stop said drum in a proper position with the doors disposed for access by an operator.

It is finally an object of this invention to construct a drum and reciprocating driving mechanism therefor which acts automatically to reciprocate said drum and whereby by manual actuation of a pin the drum may be brought to rest in the proper position for the insertion or removal of clothes therefrom.

The invention (in a preferred form) is illustrated in the drawings and hereinafter more fully described.

In the drawings: Figure 1 is a front elevation of a washing machine with a reversing gear and clothes drum mounted thereon. Fig. 2 is a section taken on line 2-2 of Fig. 1. Fig. 3 is an interior view of the reversing gear mechanism with the cover thereof removed. Fig. 4 is a section taken on line 4-4 of Fig. 3. Fig. 5 is a section taken on line 5-5 of Fig. 4. Fig. 6 is an enlarged detail view showing in elevation the clutch lever of the reversing gear mechanism. Fig. 7 is a section taken through the bevel gear of the reversing mechanism. Fig. 8 is an end elevation of the end of the bevel gear shaft of the reversing mechanism. Fig. 9 is an elevation of the cam disk secured on the bevel gear of

the reversing mechanism. Fig. 10, is a top plan view partly broken away of the perforated clothes drum, and showing the doors thereon in closed position. Fig. 11, is a section taken on line 11—11 of Fig. 10. Fig. 12 is an end elevation of the clothes drum, showing the doors thereon in open position.

As shown in the drawings: the reference numeral 1, indicates a frame for a washing machine adapted to support a semi-cylindrical tub 2, in which is journaled to rotate, the clothes drum 3.

A clothes wringer 4, is mounted on one side of the device and driving connections 15 from a motor 5, serve to operate said clothes drum and said wringer either simultaneously or independently.

For the purpose of transmitting the drive from the motor, any suitable type of bevel 20 gears, (not shown) but inclosed in a housing 6, are mounted conveniently upon the machine, and inclosed within a tubular member 7, is a sectional shaft 8, which is secured to a bevel gear within said housing 6, to 25 be driven thereby. This portion of the mechanism, however, forms no part of this invention. Said sectional shaft 8, extends through a reversing gear casing 9, and thence upwardly through another tubular 30 member 10, which is connected with the casing 11, wherein are mounted gears to drive said wringer 4. However, this invention relates only to the reversing mechanism and its association with the clothes drum of the 35 device, and the wringer driving mechanism forms no part thereof.

For the purpose of reversing the clothes drum, there is secured in one of the ends 12 thereof, a socket member 13, which is provided with a pentagonal recess 14, adapted to receive therein the similarly shaped end 15, of a bevel gear shaft 16. The bevel gear shaft 16, is journaled in said casing 9, and has secured thereon a bevel gear 17, which 45 at all times meshes with freely rotatable clutch gears 18, and 19, respectively, mounted on said shaft 8.

A rotatable slidable clutch member 20, is feathered on said shaft 8, and when shifted to either one of its extreme positions engages with one of said gears 18, or 19, to rotate said drum.

For the purpose of actuating said clutch member 20, into engagement with either one 55 of said clutch gears 18, or 19, a clutch lever 21, is pivotally mounted at its lower end within said casing 9, and loosely engages in a groove in said clutch member 20, so that as said lever is thrown into a position either 60 to the right or left of that shown in Fig. 3, one or the other of said gears 18, or 19, will be caused to rotate with said shaft 8.

For the purpose of maintaining the clutch lever in either one of its extreme positions 65 a spring detent 22, is provided on the up-

per end thereof and is adapted to engage in notches in the outer surface of said gear casing 9.

For the purpose of maintaining said clutch lever in neutral position a pin 23, is 70 slidably mounted in an aperture in a lug on the upper side of said casing 9, and is adapted when thrust inwardly, to engage in an aperture 24, in the clutch lever, to thereby positively lock the same from movement in either direction. 75

Means are provided for automatically producing a reversal of rotation of said bevel gear 17, and for this purpose a cam disk 25, is rotatably mounted thereon, and 80 is provided with a raised portion or cam element 26. Said cam disk is provided with a plurality of notches or teeth in its periphery adapted to be engaged by a stop 27, rigidly secured on the interior of said casing 9, so that with each rotation of said bevel gear 17, the passage of the cam disk by the stop 27, will cause a movement of the disk equal to the pitch of said notches or teeth in the periphery thereof. 90

Slidably mounted in a lug 28, adjacent said cam disk is a spring pressed pin 29, adapted to be normally retracted, and which, when projected, extends through the front face of said bevel gear 17, to contact 95 either one, as the case may be, of the spring bars 30, secured on said clutch lever 21, to throw said clutch member into one position or the other, the impact thereon being relieved to some extent by said spring bars 100 30. Said pin 29, is so positioned relative the cam disk as to be contacted and impelled outwardly through the bevel gear 17, whenever the raised portion 26, on said cam disk passes the same, and of course, the 105 number of notches in the periphery of said cam disk will determine the number of revolutions which may be performed by said bevel gear 17, before the same is reversed, due to the projection of said pin 29, and engagement with said clutch lever. The 110 clothes drum 3, is so connected with said bevel gear shaft 16, that the doors 31, thereon are on the top side of said drum at the instant of reversal thereof. 115

The operation is as follows: When the driven shaft 8, is rotating, an operator withdraws the pin 23, and throws said clutch member manually into either one of its extreme positions and due to the interlocking of one of said bevel gears 18 or 19, with the clutch on said shaft 8, the drum is caused to rotate. It is to be noted that the amplitude of movement of said clutch lever 21, is not sufficient to bring either one of the side edges thereof to a position beyond that of the pin 23, so that with said clutch lever in any but its neutral position, it is impossible to thrust said pin 23, inwardly. Accordingly, when it is desired to stop the ma- 120 125 130

chine, of course with the doors in the drum properly positioned for access thereto, the operator merely presses inwardly upon said pin 23, and when the reversing action takes place and the clutch lever is moved from one extreme position toward another, the pin will engage within the aperture and lock the clutch in neutral position, thus disconnecting the driving mechanism from the clothes drum, and inasmuch as the same is secured thereto with the doors thereof adapted to be positioned on the upper side thereof during the reversing movement, the consequent stoppage of the drum when the clutch is thrown to neutral position will position the drum with the doors on the upper side thereof, and convenient of access for an operator.

I am aware that details of construction may be varied through a wide range without departing from the principles of this invention. I therefore do not purpose limiting the patent granted otherwise than necessitated by the prior art.

25 I claim as my invention:

1. In a device of the class described, a clothes drum, means affording access thereto, mechanism for driving said drum alternately in opposite directions, controlling mechanism for automatically reversing said driving mechanism, and manually operated means for engaging and stopping said controlling mechanism when the latter is in neutral position, whereby said drum will be stopped at a predetermined point affording access to its interior.

2. In a device of the class described, a clothes drum, means affording access thereto, mechanism for driving said drum alternately in opposite directions, a lever for

automatically reversing said driving mechanism and having an aperture therein, and a manually operated slideable pin adapted to engage in said aperture and stop said lever as the latter moves to neutral position, whereby said drum will be stopped at a predetermined point affording access to its interior.

3. In a device of the class described, a clothes drum, means affording access thereto, mechanism for driving said drum, clutch mechanism for reversing said drum, a lever controlling said clutch mechanism and acting automatically to reverse the same, said lever having an aperture therein, and a manually operated pin for engaging said lever when in neutral position, whereby said drum will be stopped at a predetermined point affording access to its interior.

4. In a device of the class described, a clothes drum, a casing, an apertured lug integral therewith, reversing gear mechanism in said casing, a clutch lever associated with said mechanism adapted to be manually and automatically operated to cause reversal in rotation of said clothes drum, said lever having an aperture therein, and a manually operable pin slidably mounted in said lug adapted to be thrust into said aperture to lock the lever in neutral position during travel thereof from one extreme position to another to lock said clothes drum in proper accessible position.

In testimony whereof I have hereunto subscribed my name in the presence of two subscribing witnesses.

HAROLD W. EDEN.
